UNITED STATES PATENT OFFICE.

JOSEPH GASKILL, OF TRENTON, NEW JERSEY.

DESIGN FOR A ROPE-CLEAT.

SPECIFICATION forming part of Design No. 29,330, dated September 13, 1898.

Application filed August 6, 1898. Serial No. 687,993. Term of patent 7 years.

To all whom it may concern:

Be it known that I, JOSEPH GASKILL, a citizen of the United States, residing at Trenton, in the county of Mercer and State of New Jersey, have invented and produced a certain new and original Design for Rope-Cleats; and I do declare the following to be a full, clear, and exact description of the invention, such as will enable others skilled in the art to 10 which it appertains to make and use the same.

My invention relates to a design for a rope-cleat for securing the free ends of the rope used for clothes-lines, hammocks, and the like; 15 and to this end the invention consists in the configuration of the clamp illustrated in the accompanying drawings, in which—

Figure 1 is a perspective view of a cleat embodying my design. Fig. 2 is a longitudinal 20 section of the same.

The leading features of my design appear in the following description.

The cleat comprises a longitudinal base 1,

having rounded ends 2 2, provided with transverse countersunk orifices 3 3.

4 4 denote standards arising from said base and formed with their opposed walls 5 5 converging upwardly, as shown, while their opposite outer walls terminate in the longitudinal flanges 6 6, rounded at their ends. The 30 lower faces 7 7 of the flanges 6 6 and the upper faces 8 8 of the base converge inwardly toward the semicircular walls 9 9 of the standards 4 4.

Having thus fully described my design, 35 what I claim as new, and desire to secure by Letters Patent of the United States, is—

The design for a rope-cleat as herein shown and described.

In testimony whereof I have hereunto set 40 my hand in presence of two subscribing witnesses.

JOSEPH GASKILL.
